SAFETY MATCH CONTAINER

Harry George Klassen, Chicago, Ill.

Application June 10, 1932, Serial No. 616,418

9 Claims. (Cl. 206—29)

This invention relates to lighters and more particularly to lighters wherein means is provided for igniting match like members and bringing them into position for use.

5 In the ordinary use of matches and match boxes, it is necessary to remove the matches from the container and ignite them by scratching them on some abrasive material. In this ordinary use of matches they are likely to be dropped, and thereby constitute considerable fire hazard. This invention provides a device wherein match like members are easily and conveniently positioned for use without removal from the container, and wherein the matches are simultaneously positioned and ignited. The burned matches are retained within the container and are not discarded as with the ordinary match box, thereby providing a further safety consideration. The containers also provide convenient surfaces for advertising or other printed matter.

10 It is an object of my invention to provide a lighter wherein the matches are consecutively brought into position for use and simultaneously lighted. Also to provide a lighting device having one or a plurality of movable members therein, each of the members being provided with outwardly extending matchlike arms arranged to be moved with the movable members and thereby to be consecutively positioned for use and simultaneously ignited. A further object is the provision of a device including a casing or support having an opening therein and means whereby matches inclosed in the casing may be consecutively moved into alignment with the openings and simultaneously ignited. This invention also provides a convenient device wherein a stock of matches are contained within the container and means is provided whereby the matches are exposed one at a time and whereby during the movement of the match to the exposed position it is simultaneously ignited. May it be understood that said containers are constructed of fireproof material or other substantially treated material.

15 Further objects will be apparent from the specifications and the appended claims.

45 In the drawings:

Fig. 1 is a perspective view of one embodiment of my invention in which the igniting surface is on a member supported and positioned to engage the outer end of the match as it is moved to the exposed position. This type of base is constructed of wood or other suitable material, the supporting surfaces are fastened to the base by glueing or other suitable means.

50 Fig. 2 is a perspective view of another em-

bodiment of my invention in which the rotary members are off-set out of axial alignment, the igniting surface is inside the container. This type of container is constructed of a single piece of cardboard or other material.

5

Fig. 3 is a perspective view of an embodiment similar to that shown in Fig. 2 except that the rotatable members are in axial alignment.

Fig. 4 is a perspective view of the embodiment illustrated in Fig. 3 in its partially assembled form 10 before the casing has been glued or otherwise secured together.

Fig. 5 is a side elevation of one of the movable match units.

Fig. 6 is a transverse sectional view through the 15 match unit illustrated in Fig. 5 taken on a line corresponding to line 6—6 of Fig. 5.

Fig. 7 is a top plan of one of the containers or support blanks before being folded.

Fig. 8 is a sectional view through the completely assembled device and taken on a line corresponding substantially to line 8—8 of Fig. 2.

Fig. 9 is a fragmentary detailed view of a match igniting device or friction surface as a portion of the case.

Fig. 10 is a detailed sectional view of the igniting or friction device and taken on a line corresponding to line 10—10 of Fig. 9.

Fig. 11 is a perspective view of the container provided with a cover for the exposed match.

30

Referring to the drawing in detail:

The embodiment illustrated in my invention comprises a casing 1, Fig. 3, this casing is formed of a single blank which comprises sidewalls 2 and a central portion 3. The walls are provided 35 with side flaps 4, and end flaps 5.

The blank as illustrated in Fig. 7 is arranged to be folded on the dotted lines as shown in Fig. 4, the flaps 4 are then secured together by glueing or other suitable means. The end flaps 5, may be 40 secured to the intermediate section 6, the blank then forms a rigid casing or container similar to that in Fig. 3 having two compartments, each of which is arranged to support a movable match carrying member, which as in the embodiment 45 illustrated is a rotary device comprising a member 7, which may be in the form of a disk, having a plurality of outwardly extending radially disposed arms 8, the ends of which are provided with the usual ignitable match head material as shown 50 by 9. The safety flap is formed in the opening 16 and takes the position as illustrated by 13.

The disks or rotors are preferably formed of paper or other suitable material which may be pressed into form as shown. Each rotor is pro- 55

55

vided with an outwardly extending hub 10 which is arranged to extend through one of the openings 11 in the side walls 2, thereby providing bearing surface. A flap or safety cover 12, Fig. 11 5 may be used if desired, the cover is moved outwardly when the device is used. A protection flap 13, is formed downward to isolate the lighted match from the remainder of the pack. The points of ignition 15 also serve the same purpose 10 on the opposite side of the lighted match. The rotor may be formed with a bead 14, which serves to position the rotor equidistant between the compartment walls and to provide bearing surfaces therefor.

15 The casing is provided with a plurality of formed portions 15, which when the blank is folded are in oppositely disposed alignment transverse to the path of the match heads as the rotor is moved. These portions are filled or covered with a friction or other match igniting material, so that as the rotor is turned by means 20 of the outwardly extending hub 10, the consecutive match heads pass between the friction surfaces and are therefore ignited as they move into 25 position for use, in alignment with the opening 16 of the container.

It will be apparent that further modification may be made by those skilled in the art, and I therefore desire to be limited only by the prior 30 art and the appended claims.

Having thus described my invention what I desire to secure by Letters Patent is:

1. A lighter of the character described comprising a box-like container having openings 35 therein, a plurality of ignitable members in said container movable one by one into alignment with said openings, and means supported by said container for igniting said members as they are moved into alignment with said opening with a 40 flap protruding from the top or side of said opening to separate the lighted match from the unused matches remaining.

2. A lighter of the character described comprising a container having oppositely disposed 45 openings therein, a partition dividing the container into two compartments, a rotor in each compartment having radially disposed match arms, operating means integral with each rotor and an igniting portion in each compartment for 50 cooperation with the match heads and formed out of and integral with said container.

3. A lighter of the character described comprising a container having separate match compartments therein and each compartment having 55 a match exposing opening, a rotary member in each compartment having radially disposed match arms, a bearing member on each rotary member, and extending through the outer wall of said compartment to provide means for turning said rotary member and means in each of said compartments to ignite said matches as they are moved into alignment with said openings,

the axes of said rotary members being in spaced parallel relation.

4. A lighter of the character described having off set compartments therein and having a side and a top opening in each compartment said 5 side openings being out of axial alignment, a rotor in each compartment and each having a hub extending through its corresponding side opening and radially disposed match members, said top openings providing access to the ends 10 of said match members.

5. A lighter of the character described comprising a container having oppositely disposed openings therein, a partition dividing the container into two compartments, a rotor in each 15 compartment having radially disposed match arms, operating means integral with each rotor, means for igniting said matches during operation of the rotors, the axes of said rotors being in parallel spaced relation. 20

6. A lighter of the character described comprising a container having oppositely disposed openings therein, a partition dividing the container into two compartments, a rotor in each compartment having radially disposed match 25 arms, operating means integral with each rotor, means in each compartment for igniting successive matches during movement in one direction, and means for preventing movement of the matches in the opposite direction. 30

7. A container for a rotary match lighter of the character described comprising a single blank of thin material having match exposing openings, a match separating flap in each of said openings, rotor bearing openings in said blank, a 35 plurality of oppositely disposed spaced igniting surfaces on the opposite sides of said blank, said blank being foldable on a plurality of lines to provide a two compartment container having oppositely disposed match openings and substantially aligned bearing openings. 40

8. A rotor member for a lighter of the character described comprising a comparatively thin disc like fabric member having integrally formed radially disposed match arms, an integrally 45 formed outwardly extending actuating portion arranged to provide an axial bearing, and oppositely embossed stabilizing rings formed around the said axial bearing.

9. A lighter of the type described comprising a 50 single compartment container, a rotary match member having integrally formed radially disposed match arms therein, said container having a match exposing opening, abrasive surfaces formed in line with the path of the matches in 55 a side of said opening, concave match separators formed therein opposite said abrasive surfaces, an integrally formed combined bearing member and actuating knob movably supported therein and a bearing means in said container for supporting 60 the said rotor for its rotary motion.

HARRY GEORGE KLASSEN.
